FLUID COMPRESSOR

Burton S. Aikman, Wilkinsburg, Pa., assignor to
The Westinghouse Air Brake Company, Wil-
merding, Pa., a corporation of Pennsylvania

Application July 2, 1936, Serial No. 88,497

5 Claims. (Cl. 230—21)

This invention relates to compressors, and more particularly to an improved fluid compressor and control means therefor.

In order to secure high volumetric efficiency in the operation of a compressor, it is desirable that the fluid to be compressed be completely discharged from the compression chamber upon each compression stroke of the piston, without leakage of said fluid to other parts of the compressor or to the atmosphere.

One object of my invention is to provide a compressor having these advantages, which object is accomplished by employing a compressor piston adapted to operate through a body of liquid contained in the compression chamber, the resulting displacement of the liquid being effective to compress the air or other fluid, while ensuring the complete discharge of said fluid from the compression chamber.

Another object of my invention is to provide a compressor of the above type having means for utilizing the fluid compressing liquid or water as a cooling medium for rapidly dissipating the heat of compression of said fluid.

It is desirable that the compressor be operated to deliver a supply of fluid under pressure free from oily vapors, which are apt to develop due to leakage of lubricant past the compressor piston into the fluid compression chamber, or for other causes.

It is a further object of my invention to provide a compressor having water displacement means for compressing air or other fluid, in which the possibility of undesired vaporization of lubricant from the compressor into said air or fluid is obviated.

Another object of my invention is to provide a compressor embodying means for automatically varying the clearance volume within the fluid compression chamber for effecting any desired degree of loading of the compressor.

Another object is to provide power-circuit controlling means operative to effect initial unloading of the compressor prior to cutting off the power supply of the compressor driving motor.

A still further object of the invention is to provide an improved fluid compressor having automatic load controlling means associated therewith.

Other objects and advantages will appear in the following more detailed description of the invention, taken with reference to the accompanying drawings, in which:

Fig. 1 is a diagrammatic, vertical view, mainly in section, of a fluid compressor equipment

embodiment of my invention; Fig. 2 is a diagrammatic, vertical view, partly in section, of a compressor equipment embodying another form of my invention; Fig. 3 is a sectional view taken on the line 3—3 of Fig. 2; Fig. 4 is a sectional view taken on the line 4—4 of Fig. 2; Fig. 5 is a vertical, sectional view of a portion of a compressor embodying another form of my invention; Fig. 6 is a sectional view taken on the line 6—6 of Fig. 5; and Fig. 7 is a fragmentary, sectional view illustrating an alternative construction for the compressor shown in Fig. 5.

Referring to Fig. 1 of the drawings, there is provided a fluid compressor designated generally at 10, a reservoir 11 for receiving fluid compressed by the compressor, a liquid supply valve device 12, and an unloading valve device 13.

The compressor 10 comprises a crank case 15 having a crank case chamber 16 and vertical cylinder bores 17 and 18, and cylinder casing sections 19 and 20, which are mounted on said crank case in alignment with the bores 17 and 18, respectively. An elongated, hollow piston 22 is slidably mounted in the bore 17 and extends through an intermediate chamber 23 formed in the crank case and into a compression chamber 24 within the cylinder casing 19. The chamber 24, which preferably is of larger diameter and has a substantially greater volume than that displaced by the piston 22, is adapted to contain a body of liquid, such as water, hereinafter referred to as the compressing liquid.

A flexible packing gasket 26, preferably made of rubber and having an inclined flange 27, is interposed between the crank case 15 and the cylinder casing 19, the flange on said packing gasket having sealing engagement with the wall of the piston 22 for preventing escape of liquid or fluid under pressure from the compression chamber 24. A downwardly sloping collar 28 is secured to the piston 22 within the chamber 23 for deflecting possible leakage flow of liquid past the packing gasket 26 into an annular channel 29, which is formed in the lower wall of said chamber and has an open drainage port 30.

Fitted within the piston 22 and secured thereto by any suitable means, such as by a rivet 32, is a journal member 33 carrying a wrist pin 34, to which is pivotally connected the upper end of a connecting rod 35, the lower end of said connecting rod being journaled on a crank shaft 36, which is rotatably mounted in the crank case 15 and which may be driven by any suitable means (not shown).

Slidably mounted in the bore 18 is a hollow

piston 40, which is adapted to be reciprocated in a compression chamber 41 within the cylinder casing 20 through the medium of a connecting rod 42 journaled on the crank shaft 37, it being understood that the piston is otherwise constructed and arranged similarly to the piston 22 already described.

A manifold pipe 48 is provided for receiving fluid under pressure supplied from the compression chambers of the compressor, said manifold pipe having an annular flange portion 49 mounted on the cylinder casing 19, and an annular flange portion 50 mounted on the cylinder casing 20. Disposed in a chamber 51 formed in the upper portion of the cylinder casing 19 is a discharge valve 52, which is urged toward a seat 53 by a spring 54 interposed between said valve and the flange portion 49. The valve 52 is adapted to control communication between the compression chamber 24 and the manifold pipe 48. In like manner a chamber 55 is formed in the upper portion of the cylinder casing 20 and contains a discharge valve 56, which is urged into engagement with a seat 57 by a spring 58. The valve 56 is adapted to control communication between the compression chamber 41 and the manifold pipe 48.

It will be noted that the upper walls of the compression chambers 24 and 41 are so formed as to provide substantially conical surfaces 59 and 60, respectively, which slope upwardly toward the respective valve seats 53 and 57 so that there are no pockets or cavities in which air or other fluid to be compressed may lodge.

35 The cylinder casings 19 and 20 are provided with aligned valve portions 70 and 71, respectively, and an intake member 72 is clamped between said valve portions so as to form a chamber 73 in the valve portion 70 and a chamber 74 in the valve portion 71. These chambers communicate with a central passageway 75 which is connected through a passage 76 to an air intake strainer 77 of any desired type, and is also connected through a restricted passage 78 to a liquid supply pipe 79.

45 An inlet valve 81 is provided for controlling communication from the passageway 75 through the chamber 73 and apertures 82 in the cylinder casing 19 to the compression chamber 24. Similarly, an inlet valve 84 is disposed in the chamber 74 for controlling communication from the passageway 75 to the compression chamber 41 by way of said chamber and apertures 85 in the cylinder casing 20. Springs 87 and 88 are provided for urging the respective valves 81 and 84 to their seated positions.

The supply valve device 12 is provided for controlling the supply of compressing liquid to the compression chambers 24 and 41 of the compressor, and may comprise a casing section 90 having a chamber 91 connected to a supply of liquid (not shown) under a predetermined pressure head through a pipe and passage 92. A manually adjustable valve of any desired type, such as the rotary plug valve 88, may be interposed in the passage 92 for regulating the rate of supply of liquid to the chamber 91. A casing section 93 is mounted on the casing section 90, and a flexible diaphragm 94 is clamped between the casing sections 90 and 93, so as to form at one side thereof a chamber 95 and at the other side a chamber 96. The chamber 96 is connected to the supply pipe 79 and is separated from the chamber 91 by an apertured wall 97.

75 Disposed in the chamber 91 of the valve device

12 is a valve 99, having a stem 100 which extends through the aperture in the wall 97 and is secured to the diaphragm 94, said valve being adapted normally to engage a seat formed on said wall for cutting off communication between the chambers 91 and 96. The diaphragm 94 is adapted to be subjected to fluid pressure for controlling operation of the valve 99, fluid under pressure being supplied from the compression chamber 41 of the compressor by way of a port 101 formed in the wall of the cylinder casing 20, past a non-return check valve 102, which is disposed in a valve chamber 104 in said casing, and through a pipe 103 to the chamber 95.

For cooling the fluid under pressure and any accompanying compressing liquid supplied from the compressor through the manifold pipe 48, there is provided a cooling pipe 105, which is connected to the manifold pipe, and which communicates by way of a branch pipe 106 with the reservoir 11.

In addition, the pipe 105 communicates with a chamber 107 in an automatic drain valve device 108, which chamber is connected through a conduit 109 with the lowermost portion of the reservoir 11. Disposed in the chamber 107 is a normally seated valve 111 operably connected to a lever 112, which is fulcrumed on a pin 113 carried by a lug formed within the casing. A float 114 is mounted on the lever 112 and is adapted to effect the opening and closing of said valve according to the level of liquid in the chamber 107 for controlling communication from said chamber to a drain pipe 115.

30 In order to provide for the automatic unloading of the compressor in accordance with the fluid pressure built up in the reservoir 11, unloading means is provided which is automatically operative in response to a predetermined reservoir pressure for reducing the amount of compressing liquid contained in the compression chambers 24 and 41, thereby automatically varying the volumetric efficiency of the compressor.

35 Referring to Fig. 1 of the drawings, the unloading valve device 13 comprises a hollow casing 117 within which is mounted a vertical sleeve member 118, having a bore formed in vertical alignment with a substantially conical valve seat 120, which is formed in the lower portion 50 of said casing adjacent a discharge opening 121.

40 Clamped between a cover plate 122 and the upper end of the casing 117 of the unloading valve device 13 is a flexible diaphragm 123, which has at its upper side a chamber 124 connected by way of a pipe 125 with the reservoir 11, and which has at the other side a spring chamber 126. A follower member 127 engages the lower side of the diaphragm 123 and is slidably mounted in the vertical bore within the sleeve member 118, 60 the lower end of said member having screw-threaded connection with the stem 128 of a valve element 129, which is formed substantially complementary to and is movable into and out of engagement with the valve seat 120.

45 Ports 131 and 132 are formed in the conical face of valve seat 120, the port 131 communicating by way of a pipe 133 and a passage 134 in the cylinder casing 19 of the compressor with the compression chamber 24, and the port 132 70 communicating by way of a pipe 135 and a similar passage (not shown) in the cylinder casing 20 with the compression chamber 41. A spring 136 is disposed in the chamber 126 of the unloading valve device between the head 137 of the 75

follower member 127 and the sleeve member 118 for urging the diaphragm 123, the follower, and the valve element 129 upwardly, so that the valve element normally engages the seat 120.

5 In the following description of the operation of the compressor equipment, it is assumed that the manually operated valve 98 has been adjusted to permit flow of liquid at the desired rate from the liquid supply through the pipe and 10 passage 92 to the chamber 91 of the liquid supply valve device 12, while the compression chambers 24 and 41 of the compressor 12, which are adapted to contain liquid, are initially empty. Since the fluid pressure in the reservoir 11 is 15 initially low, the spring 136 in the unloading valve device 13 maintains the valve 129 in seated position.

When the crank shaft 36 is rotated, the pistons 22 and 40 are reciprocated in the usual manner 20 through the medium of the respective connecting rods 35 and 42. During the initial compression strokes of the piston 40, sufficient fluid pressure is built up in the compression chamber 41 to unseat the check valve 102 and force fluid under pressure 25 through the pipe 103 to the chamber 95 of the liquid supply valve device 12. Fluid under pressure thus supplied to the chamber 95 moves the diaphragm 94 downwardly and thereby unseats the valve 99. The plug valve 98 having been set 30 in a position to supply liquid at the desired rate of flow through the passage 92 to the chamber 91, liquid is then free to flow from said chamber and past the unseated valve 99 to the chamber 96.

Upon each suction stroke of the piston 40, a 35 partial vacuum is created in the compression chamber 41, so that air or other fluid is drawn into said chamber by way of the strainer 77, the passage 76, and through the valve chamber 74 and passages 95. At the same time, a quantity 40 of liquid is also drawn from the chamber 86 of the supply valve device 12 through the pipe 79 and restricted passage 78 to the passageway 75, and thence by way of the other communications just mentioned into the compression chamber 41.

45 Similarly, upon the suction stroke of the piston 22, air or other fluid is drawn through the strainer 77, passage 76, passageway 75, past the unseated inlet valve 81 and through the valve chamber 73 and passages 82 into the compression chamber 24, while liquid is drawn into said chamber by way of the restricted passage 78 and through said other communications.

As compressing liquid is thus supplied to the 50 compression chambers 41 and 24, liquid flows through the pipes 133 and 135 to the seat of the closed unloading valve 129 and gradually fills said chambers, so that the clearance volumes of both chambers are gradually reduced. The displacement of the liquid upon further compression 55 strokes of the pistons 40 and 22 thereby causes an increased fluid pressure to be built up, the fluid compressed in the chamber 24 being forced past the discharge valve 52 and through the manifold 48, cooling pipe 105 and pipe 106 to the reservoir 11, and the fluid compressed in the chamber 41 unseating the discharge valve 56 and flowing by way of the same communications to the reservoir 11.

After a short period of operation, compressing 60 liquid will have been supplied in the manner just described to the compression chambers 24 and 41 in quantities such that, when displaced by the pistons 22 and 40, respectively, at the upper limits of the respective strokes thereof, the compressing liquid entirely fills the compression

chambers, with the result that complete expulsion of the fluid under pressure from said chambers to the manifold 48 is effected during the successive compression strokes of the pistons.

When the compressor 10 is thus operating at its 5 full volumetric efficiency, since a quantity of compressing liquid is drawn from the supply into each of the compression chambers 24 and 41 upon the suction strokes of the pistons 22 and 40, respectively, each piston as it approaches the upper 10 limit of its compression stroke, will force substantially the same quantity of liquid from its compression chamber past the unseated discharge valve and into the manifold 48.

The compressing liquid, being in direct contact with the air or fluid being compressed, is thus enabled to absorb heat therefrom, and as portions of the liquid are forced from the compression chambers into thermal contact with the discharge valves, the latter are thereby 20 constantly cooled during operation of the compressor.

It will be apparent that the compressing liquid is in this way utilized as a means for absorbing and carrying off from the compressor the heat of compression of the air or other fluid, the hot 25 liquid, together with the air or fluid under pressure, being cooled while flowing from the manifold 48 through the cooling pipe 105. As the fluid under pressure flows from the pipe 105 through the pipe 106 into the reservoir 11, most 30 of the liquid is separated therefrom and flows downwardly from the pipe 105 into the chamber 107 of the automatic drain valve device 108, while liquid condensed in the reservoir collects 35 in the lowermost portion thereof, which is connected with said chamber through the pipe 109.

If the level of liquid in the chamber 107 and in the reservoir 11 rises above a predetermined point, the float 114 is adapted to operate the lever 112 so as to open the valve 111. Liquid is then 40 discharged from the reservoir 11 and the connected chamber 107 past the unseated valve 111 and through the pipe 116.

When the pressure of the fluid in the reservoir 11 has been built up to a predetermined value, 45 fluid under pressure supplied therefrom to the chamber 124 of the unloading valve device 13 and acting on the diaphragm 123 overcomes the force of the spring 136, and moves the diaphragm, the follower 127, and the valve 129 downwardly, 50 thereby moving the valve 129 out of sealing engagement with the seat 120. Compressing liquid is then quickly discharged from the compression chamber 24 of the compressor 10 by way of the passage 134, pipe 133, port 131 and the discharge 55 opening 121, and also from the compression chamber 41 by way of the pipe 135, port 132, and said discharge opening.

As a result of this discharge of compressing liquid from the compression chambers of the 60 compressor, a clearance volume is created in each of said chambers at the end of the compression stroke of the respective piston therein, so that the compressor is thereby unloaded. Operation of the compressor may be continued, although 65 the pressure of air or other fluid thereafter compressed in said chambers will be insufficient to cause the unseating of the discharge valves 52 and 56 against the forces of the springs 54 and 58, respectively.

When the pressure of air or other fluid in the 70 reservoir 11 is reduced by withdrawal of fluid under pressure therefrom for any desired purpose, the fluid pressure in the chamber 124 of the unloading valve device 13 is correspondingly re- 75

duced, and the spring 136 is enabled to move the diaphragm 123, follower 127 and valve 129 upwardly so as to seat the valve. With the valve 129 closed, continued operation of the compressor 5 is then effective to cause the compression chambers to be again filled with compressing liquid in the manner hereinbefore described, so that the compressor is rendered operative to compress air or other fluid.

10 Referring to Fig. 2 of the drawings, in which is illustrated a modified form of my invention, there is provided a compressor 140 of the two-cylinder type, a driving motor 141 for operating the compressor by means of suitable gearing (not shown), a liquid supply valve device 142, a liquid reservoir 143, a reservoir 144 for receiving fluid under pressure, and an automatic unloading control device 145.

The compressor 140, the operative principle of 20 which is similar to that of the compressor 10 shown in Fig. 1, and hereinbefore described, comprises a crank case 147 having a crank case chamber 147a and provided with vertical portions 148 and 149, on which are mounted cylinder casings 25 150 and 151, respectively.

A piston 152 is slidably mounted in a bore formed in an interior sleeve portion 153 of the crank case within the vertical portion 149, the piston having an enlarged head 154 and a skirt portion 155, which is adapted to overhang the sleeve portion 153 and to project into a chamber 156 surrounding said sleeve portion. The piston 152 is adapted to be operated through the medium of a connecting rod 157, which is connected to a 30 wrist pin 158 carried by said piston, while the connecting rod may be journaled on the usual crank shaft (not shown), the head 154 of said piston being arranged to reciprocate in a compression chamber 159, which is formed in the cylinder casing 151 and is of substantially larger diameter than said head. The compression chamber 159 is adapted to contain a quantity of compressing liquid, as hereinafter described.

Oil for lubricating the piston and bearing surfaces may be supplied by any desired means (not 40 shown). For collecting lubricating oil wiped from the piston 152, an annular groove 161 is formed in the upper rim of the sleeve portion 153 adjacent the piston bore therein, said groove being 50 connected through a passage 162 with a chamber 163 formed in the crank case 147. The chamber 163 is adapted to communicate with the crank case chamber 147a by way of a bore 165, valve chamber 166 and apertures 167 formed in a valve cage 168 which has screw-threaded connection 55 with the interior wall of the crank case. A ball check valve 169 is preferably disposed in the valve chamber 166 for preventing back flow of air or vapor from the crank case chamber, said valve being urged to its seat by a spring 170.

Clamped between the vertical portion 149 of the crank case and the cylinder casing 151 is an annular packing gasket 173, which has an upwardly inclined flange 174 adapted to maintain 65 sealing engagement with the skirt portion 155 of the piston 152. An annular supporting member 175 is preferably interposed between the vertical portion 149 and the packing gasket 173 for resisting the downward thrusts to which the gasket 70 may be subjected due to the force exerted by the liquid under pressure in the chamber 159.

A drain passage 176 is connected to the lowermost portion of the chamber 156 for carrying off any liquid which might seep past the packing gasket 173, the drain passage being of a restricted

size so as to permit sufficient build up of fluid pressure in the chamber 156 upon each downward stroke of the piston 152 to force oil collected in the depression 161 through the passage 162, chamber 163 and bore 165 and thence past the check valve 169 to the crank case chamber 147a. 5

In order to promote effective cooling of the air or other fluid compressed in the compression chamber 159, a cooling grid 180 is mounted in the upper portion of the chamber beyond the limit of 10 travel of the piston head 154, the top of the grid being adapted to fit within the substantially conical upper wall of the cylinder casing 151. The cooling grid 180 may be constructed in any suitable form to provide a large surface area, and, 15 as is best shown in Fig. 4 of the drawings, the grid may comprise a vertically arranged sheet or plate of substantially spiral form, the outer portion of the grid being secured to the cylinder casing 151 by any suitable means, such as by welding. 20

Disposed in a valve chamber 181 formed in the upper portion of the cylinder casing 151 is a discharge valve 182, which is adapted to engage a seat 183 for controlling communication between the compression chamber 159 and the valve chamber. 25 The discharge valve 182 has a hollow stem 184 slidably mounted in a suitable bore in the adjacent end of an exhaust manifold pipe 185, which is mounted on the cylinder casings 150 and 151. A spring 186 is interposed between the valve 30 stem 184 and a wall of the manifold pipe 185 for urging the discharge valve 182 to its seated position. The valve chamber 181 communicates by way of the manifold pipe 185 and a pipe 187 with the reservoir 144. In actual practice the 35 reservoir 144 may preferably be located on a lower level than the manifold 185 and pipe 187, so as to ensure proper flow thereto of liquid discharged from the compressor.

A clearance control valve device 188 is provided 40 for automatically regulating the amount of compression liquid maintained in the compression chamber 159. The clearance control valve device comprises a casing, which may be formed integral with the cylinder casing 151, and which 45 has a valve chamber 190 connected through an aperture 191 with the lowermost portion of the compression chamber 159. Disposed in the valve chamber 190 is a valve 192 which is adapted to be normally held seated by a spring 193 interposed between said valve and the wall of the 50 chamber. The valve 192 has a fluted stem 195 mounted to slide in a suitable bore in the casing, which bore connects the valve chamber 190 through a chamber 196 to a liquid discharge pipe 55 197.

A cover 199 is mounted on the clearance control valve casing, and a flexible diaphragm 200 is between said cover and the casing, forming a pressure chamber 201 which is connected by way of a 60 passage and pipe 202 with a control pipe 203. The diaphragm 200 is adapted to operate the valve 192 through the medium of a follower element 204, which is interposed between said diaphragm and the stem 195 within chamber 196. 65

It is not deemed necessary to show and describe in detail the internal construction and arrangement of the parts of the other compressor cylinder included within the vertical casing portion 148 and cylinder casing 150, as it will be 70 understood that this cylinder is substantially the same as that comprising the vertical portion 149 and cylinder casing 151 hereinbefore described.

Associated with the cylinder casings 150 and 75 151 is an intake manifold 206, which communi-

cates with the atmosphere, or the source of fluid to be compressed, by way of a filter 207, and which is adapted to conduct compressing liquid supplied through a pipe 208 by the liquid supply valve device 142 to the respective compression chamber within the cylinder casings 150 and 151, as will be hereinafter described.

Each of the cylinder casings 150 and 151 of the compressor is provided with an inlet valve means for controlling communication between the intake manifold 206 and each of the compression chambers. For the purpose of illustration, the inlet valve means associated with the cylinder casing 150 is shown in Fig. 3 of the drawings, said means comprising a valve 210 which is disposed in a valve chamber 211 connected with the compression chamber within said casing, and a spring 213 adapted to urge said valve to its seated position for preventing back flow from

20 said valve chamber to the inlet manifold pipe 206.

The liquid supply valve device 142 comprises casing sections 215 and 216 having clamped therebetween a flexible gasket 217, which forms on one side a pressure chamber 218 connected 25 to the control pipe 203, and on the other side a valve chamber 219 communicating with the pipe 208, and through a chamber 220 and pipe 221 with the liquid reservoir 143. Disposed in the valve chamber 219 is a normally open valve 30 223, which has a stem 224 secured to the diaphragm 217 by means of a nut 225 or other suitable means, and which is adapted to engage a seat 226 for cutting off communication between the chambers 220 and 219.

35 The liquid reservoir 143 is located above the level of the compressor 140 so as to provide the desired liquid pressure head, and is adapted to be supplied with liquid by way of a pipe 228, leading from a suitable source of liquid, not shown, a manually adjustable valve 229 being interposed in said pipe for regulating the flow of liquid. The reservoir 143 is equipped with a float valve 230, which is contained in an apertured cage 231 mounted within the reservoir, the 40 float valve being adapted to engage a seat 232 to cut off communication from the reservoir to atmosphere when the liquid reaches a predetermined level. The reservoir 143 is preferably adapted to contain sufficient liquid to fill the 45 compression chambers of the compressor after said compressor has been completely unloaded.

The unloading control device 145 is designed to operate in response to a predetermined maximum pressure of the air or other fluid supplied by the compressor 140 to the reservoir 143 first to effect the rapid unloading of the compressor, so that the current drawn by the driving motor 141 will be thereby reduced, and then to cut off the 50 supply of current to said motor. Means is also included in the unloading control device 145 for automatically effecting the unloading of the compressor when the supply of current to the driving motor 141 is cut off for any reason. As shown in the drawings, the unloading control device 55 145 comprises a casing 235 containing a fluid pressure responsive control valve 236 for automatically varying the quantity of compressing liquid held in the compression chambers of the compressor 140, and a pressure controlled switch device 237 associated with said casing for controlling the supply of current delivered to the driving motor 141.

The control valve 236 is slidably mounted in a chamber 238 communicating through a passage 50 203a with the pipe 203, and is adapted to engage

a seat 233 for controlling communication between the chamber 238 and a chamber 239a, which is connected by way of a passage and pipe 239 with the reservoir 144. The valve 236 is of the snap action type, the area thereof which is normally 5 within the seat 233 and exposed to the chamber 239a being less than the total pressure area of the valve when unseated. The valve 236 is provided with grooves 236a formed therein adjacent the wall of the chamber 238 for permitting communication past the valve within said chamber, which is normally open to the atmosphere through a passage 234. The valve 236 is adapted to engage a seat 240 which is of larger diameter than the seat 233 and is formed on the outer wall 10 of the chamber 238, for closing the atmospheric passage when the valve is operated to establish communication between chambers 239a and 238.

For urging the valve 236 toward seated position a spring 241 is provided, one end of which 20 has a hook formed thereon that is adapted to engage one of a plurality of notches in a lever 242, which is pivotally connected to the casing 235 and acts through a stem 243 to press the valve 236 into engagement with the seat 233. 25 The other end of the spring 241 is connected to an adjustable tensioning element 244 which is fitted in a bore in a lug 248 of the casing, said element being adapted to be locked into the desired position by means of lock nuts 244a having 30 screw-threaded connection therewith.

The switch device 237 comprises a movable contact 260 adapted to bridge stationary contacts 261 and 262 for controlling a power circuit through which current is supplied for operating 35 the driving motor 141, which circuit includes a conductor 263 leading to a suitable power generating means (not shown), the switch contacts 262, 260 and 261, a conductor 264, the motor 141, and a conductor 265, which in turn is connected 40 to said generating means. The stationary contacts 261 and 262 are mounted on an insulator member 267, which is carried by the upper portion of the casing 235, as shown in the drawings.

For operating the movable contact 260 of the 45 switch device 237 there is provided a pair of pistons 245 and 246, which are slidably mounted in a central bore formed in the casing 235 and which are joined by an integral stem 247. The piston 246 has a stem 249 which extends upwardly through an opening in a sleeve portion 250 of the casing. The movable contact 260 is secured to, but insulated from, the upper end of the stem 249. A spring 253 is interposed between the piston 246 and the upper wall of the sleeve portion 55 250 for normally maintaining the movable contact in engagement with the stationary contacts 261 and 262.

Formed between the pistons 245 and 246 is a chamber 251, which is connected by way of a 60 passage 252 with the passage 203a, said chamber being adapted to contain a body of oil or other liquid. The piston 245 is provided with apertures 254 communicating with the chamber 255 which is formed at the lower side of said piston, 65 communication between said apertures and the chamber 251 being controlled by a light plate element 256, which is loosely fitted on the stem 247 and is adapted to overlap the apertures 254. The plate element 256 is adapted to permit free 70 flow of liquid from the chamber 255 to the chamber 251 by way of the apertures 254 in the piston 245, and has extending therethrough a restricted port 258 which is adapted to register with one of the apertures 254 for permitting only a limited 75

flow of liquid in the opposite direction. Any suitable means (not shown) may be employed for preventing undesired turning of the plate element 256 relative to the stem 241.

- 5 A vertical groove 259 of substantial flow capacity is formed in the inner wall of the casing 235 for establishing communication between the chambers 255 and 251 upon a partial movement of the piston 245 toward its uppermost position.
- 10 It will be apparent that, upon full upward movement of the connected pistons 245 and 246, stem 249 and contact element 260, an annular bead 246a of the piston 246 will be brought into sealing engagement with a gasket 257 secured within the central bore of the casing 235, while the movable contact 260 will be moved out of engagement with the contacts 261 and 262.

Means is provided for actuating the control valve 236 to cause unloading of the compressor 20 140 when the supply of power to the motor 141 is cut off for any reason, said means including a rod 270 which is slidably mounted in a suitable bore in the lug 248 and is arranged to engage the lower end of the lever 242 for relieving the valve 236 of the pressure of the spring 241 and thereby permitting the valve to be forced from its seated position by a relatively light fluid pressure acting in the chamber 239a. A spring 271 is interposed between the lug 248 and a collar 272 on 30 the end of the rod 270 adjacent the lever 242 for urging said rod toward said lever, the power of the spring 271 being greater than that of the spring 241.

The other end of the rod 270 is pivotally connected by means of a pin 273 to the lower portion of an armature 274, which is journaled intermediate its ends on a pin 275 carried by a lug 276 formed on a magnetic core element 277, said element being mounted on the casing 235. Disposed around the core element 277 is a magnet coil 279, which is connected by means of conductors 281 and 282 to the respective conductors 263 and 265 intermediate the power source and the switch device 237, said coil being adapted 45 when energized to exert sufficient magnetic pull on the armature 274 to cause the upper portion thereof to engage the core element 277, thereby maintaining the rod 270 out of engagement with the lever 242 against the force of the spring 271, as shown in the drawings. The rod 270 is provided with a stop collar 283 adapted to engage the lug 248 for limiting movement of said rod toward the left-hand by the spring 271, and for thereby preventing movement of the armature 50 55 274 beyond the magnetic field of the coil 279.

It is assumed that, before the compressor 140 is operated, both compression chambers thereof are empty and the reservoir 144 is at atmospheric pressure, while the chamber 218 of the 60 supply valve device 142 is open to the atmosphere through the pipe 203, passage 203a, chamber 238 and passage 234, so that the valve 223 of that device is unseated. In order to condition the compressor for operation, the valve 229 is opened to 65 permit the supply of compressing liquid at the desired rate of flow through the pipe 228, the liquid reservoir 143, the pipe 221, the chamber 220 in the liquid supply valve device 142, past the open valve 223, and through the pipe 208 to the intake 70 manifold 206. The flow of liquid into the reservoir continues until the float valve 230 is raised into engagement with the seat 232.

When it is desired to start the compressor, the circuit is closed for supplying current to the motor 75 141 by way of the conductor 263, switch contacts

262, 260 and 261, conductor 264, the motor, and the return conductor 265, thereby operating said motor to reciprocate the pistons of the compressor 140 in the usual manner. The supply of current through the motor circuit also energizes 5 the magnet coil 279, and the armature 274 is then pulled into engagement with the core element 277.

On this movement of the armature 274 the rod 270 is moved against the spring 271, thereby compressing this spring and relieving the lever 242 of the force of this spring, so that the spring 241 moves the lever 242. This movement of the lever 242 is transmitted through the stem 243 to move the valve 236 into engagement with the seat 233 15 so as to cut off communication between the reservoir 144 and the passage 203a, and to connect the chamber 201 of the clearance control device 188, and the chamber 218 of the liquid supply 20 device 142 to the atmosphere.

As illustrative of the operation of both pistons of the compressor 140, it is evident that as the piston 152 moves downwardly in the suction stroke, compressing liquid is drawn into the compression chamber 159 from the manifold 206, 25 said chamber being rapidly charged with compressing liquid supplied from the liquid reservoir 143 as already described. Thereafter, upon each suction stroke of the piston 152, air or other fluid to be compressed is drawn through the filter 207 30 and the manifold 206, and past the inlet valve into the upper portion of the compression chamber 159 containing the cooling grid 180, while the continued supply of compression liquid to said chamber is also effected at a rate determined by 35 the setting of the valve 229.

It will be understood that, when piston 152 is at its lowermost position, substantially the full surface area of the grid 180 is exposed to the air or gas in the compression chamber 159. As the piston 152 moves in its compression stroke to displace the body of liquid contained in the compression chamber to compress the air or gas therein, the heat of compression of this gas is at least partially absorbed by the grid 180 by reason 40 of its large surface area, and the grid then transfers the heat to the compressing liquid as it rises into thermal contact therewith. Since the quantity of liquid supplied to the compression chamber during the previous suction stroke, in addition to that already in this chamber, is more 45 than enough to fill the chamber when the piston 152 completes its compression stroke, the top and hottest portion of the body of liquid is thereby 50 expelled past the discharge valve 182, together 55 with the air or other fluid under pressure, as the piston approaches its uppermost position. The liquid and fluid under pressure then flow by way of the manifold 185 and pipe 187 to the reservoir 144, and the liquid may thereafter be disposed 60 of by one of the methods disclosed in the other 65 embodiments of my invention.

When the pressure of fluid supplied to the reservoir 144 has been built up to the desired maximum, as determined by the setting of the spring 65 241 of the unloading control device 145, the fluid under pressure supplied by way of the pipe and passage 239 to the chamber 239a shifts the valve 236 away from the seat 233 and into engagement with the seat 240. Fluid under pressure is then 70 supplied from the chamber 239a through the chamber 238 to the passage 203a, and thence by way of the pipe 203 and pipe and passage 202 to the chamber 201 in the clearance control valve 75 device 188, thereby moving the diaphragm 208, 75

follower element 204 and stem 195 so as to unseat the valve 192. With the valve 192 unseated, compressing liquid is drained from the compression chamber 159 of the compressor by way of the aperture 191, valve chamber 190, past said valve and through the chamber 196 and drain pipe 197, thereby effecting unloading of said compressor in the manner already described, it being understood that this operation is at the same time performed in both cylinders of the compressor.

Fluid under pressure supplied to the pipe 203 as just described also flows to the chamber 218 in the liquid supply valve device 142 and moves the diaphragm 217, stem 224 and valve 223 upwardly until the valve engages the seat 226, thereby cutting off further supply of compressing liquid to the compression chambers of the compressor.

Meanwhile fluid under pressure supplied from the passage 203a by way of passage 252 to the chamber 251 in the unloading control device 145 acts upwardly against the piston 246, and also acts on the surface of the oil or other liquid so as to force slow flow thereof from the chamber 251 through the restricted port 258 of the element 256 and the adjacent passage 254 in the piston 245 to the chamber 255 therebelow. The connected pistons 246 and 245 are thereby gradually shifted upwardly together with the stem 249 and the movable contact 260, it being noted that this initial upward movement of the elements of the switch mechanism does not serve to disengage the movable switch contact 260 from the stationary contacts 261 and 262, which are of such length as to permit an initial movement of the movable contact relative to the stationary contacts before the circuit is interrupted.

The rate of flow of liquid from the chamber 251 to the chamber 255 through the restricted passage 40 258 is such that the operation of the movable contact 260 is retarded for a sufficient time interval to permit the compressor to be substantially unloaded, as hereinbefore described.

After a certain amount of upward movement 45 of the piston 245, additional communication is established around the piston by way of the groove 259 in the wall of the casing 285, whereupon further flow of the oil from the chamber 251 to the chamber 255 is permitted at a fast rate, and fluid pressure in the chamber 251 is enabled to shift the pistons 246 and 245, stem 249 and movable contact 260 upwardly with a snap-like action, thereby quickly disengaging the movable contact from the stationary contacts 261 and 262 so as to cut off further supply of current to the driving motor 141. The compressor having already been substantially unloaded, the current taken by the driving motor 141 is reduced to a minimum, so that the final operation 60 of the switch device 237 to interrupt the current supply circuit is thus accomplished with minimum arcing at the switch terminals.

It will be understood that while the valve 223 of the supply valve device 142 is seated, liquid 65 continues to flow by way of the valve 229 and pipe 228 to the reservoir 143 until the float valve 230 is seated, the reservoir being then substantially filled.

If the pressure of fluid in the reservoir 143 is now caused to fall below the pressure required 70 to maintain the valve 230 in engagement with the seat 240 in the unloading control device 145, the spring 241 becomes effective to operate the lever 242 so as to move the valve 230 into engagement 75 with the seat 233, the valve at the same time

moving away from the seat 240 for opening communication from the chamber 238 through the passage 234 to the atmosphere. Fluid under pressure is then vented from the chamber 251 by way of the passages 252 and 203a, chamber 238 and 5 passage 234, so as to permit the spring 253 to force downwardly the piston 246, stem 249 and movable contact 260, together with the stem 241 and piston 245, the plate element 256 being shifted on the stem 247 away from the piston 245 to 10 permit rapid flow of oil from the chamber 255 through the passages 254 to the chamber 251. The movable contact 260 is thus operated to bridge the stationary contacts 261 and 262, so that current is again supplied to the motor 141 15 for operating the compressor 140.

At the same time, fluid under pressure is vented from the chamber 201 of the clearance control valve device 188 by way of the passage and pipe 202, pipe 203, passage 203a, chamber 238 and 20 atmospheric passage 234, so that the spring 183 is enabled to seat the valve 192 for cutting off further communication between the compression chamber 159 and the drain pipe 197. Fluid under pressure is also vented by way of the communications already mentioned from the chamber 218 of the liquid supply valve device 142, permitting the valve 223 to be unseated by the pressure of liquid acting thereon within the seat rib 226. Compressing liquid is then supplied from the 30 reservoir 143 to the compression chambers of the compressor 140 in the manner hereinbefore described, so that said compressor will again be 35 loaded.

If the power circuit through the conductors 263, 35 265 is interrupted, so as to cut off the supply of current to both the motor 141 and to the magnet coil 279 on the unloading control device 145, the armature 274 is relieved of magnetic pull toward the core element 277 and the spring 271 40 then shifts the rod 270 to the left. Upon engagement of the rod 270 with the lower end of the lever 242, the further expansion of the spring 271 overcomes the opposing force of the lighter spring 241, and moves the lever 242 away from the stem 45 243 permitting the valve 236 to be moved from the seat 233 by the fluid under pressure in the chamber 239a and in the connected reservoir 144.

With the valve 236 thus opened, the compressor 40 140 will be unloaded in the manner hereinbefore described. It will thus be seen that the unloading control device is adapted to function, when the compressor is stopped for any reason, automatically to effect unloading of the compressor, so that the compressor will always be initially unloaded when it is desired to resume operation thereof.

Another form of my invention is disclosed in Fig. 5 of the drawings, in which is shown a compressor comprising a piston casing section 300, a 60 liquid displacing piston 301 operatively mounted therein, and an enlarged cylinder casing section 302 mounted on said piston casing and having a compression chamber 303. In this embodiment of the invention there is associated with the compressor means for collecting compressing liquid discharged from the compression chamber, cooling said liquid, and then returning the same to the compression chamber, which means comprises a liquid trap 305 communicating through a 70 pipe 305a with the lowermost portion of the air reservoir 306, a cooling pipe 307, and a liquid supply reservoir 308.

As shown in Fig. 5 of the drawings, the diameter of the compression chamber 303 within the 75

cylinder casing section 302 is several times that of the piston 301, the chamber being adapted to contain a body of compression liquid of considerably greater volume than that displaced by said piston, so that the extent and the speed of the alternate rise and fall of the liquid in said chamber caused by reciprocation of the piston will be relatively less than the length of stroke and speed of the piston. It will be apparent that undesired surging of the compressing liquid in the compression chamber 303 is thereby minimized, so that a relatively high piston speed may be permitted without causing undue pounding of the compressing liquid against the walls of the casing section 302.

15 A horizontally disposed baffle 309 comprising a plate having a plurality of holes therein is mounted within the compression chamber 303, above the upper limit of travel of the piston 301, said baffle being adapted to check surging of the compressing liquid at the surface thereof, so as to ensure that the surface of the liquid will be maintained substantially even for preventing undesired mixture thereof with the air to be compressed during operation of the compressor. Mounted between the baffle 309 and the upper wall of the compression chamber 303 is a cooling grid 310, which in the embodiment of my invention being described comprises a hollow central core 311 provided with radially extending, vertically arranged plate portions 312, as best shown in Fig. 6 of the drawings. The function of the cooling grid 310 is similar to that of the cooling grid 180 shown in Fig. 2 of the drawings and already explained.

35 A flexible packing gasket 314 and an annular supporting member 315 are interposed between the piston casing section 300 and the cylinder casing section 302, the inner portion of said gasket being in sealing engagement with the piston 301 for substantially preventing leakage of compressing liquid from the chamber 303.

45 It will be noted that the piston 301 has a substantially conical top portion 316, so that the piston upon its compression stroke tends to force the displaced liquid laterally and outwardly within the compression chamber 303. If desired, the piston 301 may be adapted to reciprocate within a cylindrical hood 318, as shown in Fig. 7 of the drawings, for further ensuring displacement in lateral directions of the compressing liquid upon the upward strokes of said piston, the hood being mounted within the cylinder casing section 302 and having a plurality of vertically extending apertures such as the slots 319 formed in the wall 55 of the hood for permitting free passage of the liquid to and from the compression chamber 303.

An inlet valve 320 is provided for controlling communication between an intake chamber 321 and the compression chamber 303, this valve being urged toward its seated position by a spring 322. The intake chamber 321 communicates with a passage 323 leading from an air filter 324.

65 Mounted in a valve chamber 326 above the cooling grid 310 is a discharge valve 327, which is urged toward seated position by a spring 328 and is adapted to control communication from the compression chamber by way of said chamber 326 with a chamber 329 formed in a cap 330, 70 which is carried by the cylinder casing section 302. The chamber 329 communicates with the reservoir 306 by way of a pipe 342.

The liquid supply reservoir 308 has a chamber 332 open to the atmosphere by way of an opening 75 333 in the upper wall thereof. A tube 334 having

a restricted passage 335 is mounted within the reservoir 308, the open end of said tube extending downwardly into the chamber 332, and the other end thereof being connected by way of a pipe 334a with the intake chamber 321 of the 5 compressor. Contained in the chamber 332 is a float 336 having a stem 336a which is pivotally mounted on a pin 337 carried by a lug 338 formed within the reservoir 308. The free end of the stem 336a is pivotally connected to the upper end 10 of a pin valve 340, which is adapted to control communication from the chamber 332 to the cooling pipe 307.

The cooling pipe 307 may be of any suitable form for providing the desired cooling surface, 15 and may have associated therewith a fan 341 for effecting circulation of air over the pipe. The trap 305 and the pipe 305a are adapted always to contain a quantity of liquid sufficient to prevent flow of air or other fluid under pressure from 20 the reservoir 306 through said trap to the cooling pipe 307. The trap 305 is connected by way of a pipe 343 with a pipe 342, which communicates at one end with the reservoir 306, and at the other end with the chamber 329 in the cap 330 above 25 the discharge valve of the compressor.

Assuming that the necessary quantity of compressing liquid has been initially supplied to the compression chamber 303 of the compressor, and that the reservoir 308 also initially contains sufficient liquid to cause the float 336 to maintain the valve 340 closed, the principle of operation of the piston 301 to effect the substantially isothermal compression of air or other fluid in the compression chamber 303 is similar to that of the 35 hereinbefore described operation of the other embodiments of my invention as shown in Figs. 1 and 2 of the drawings.

In operation, upon the compression strokes of the piston 301, fluid under pressure together with 40 a quantity of compressing liquid is forced past the discharge valve 327, and through the chambers 326 and 329 to the pipe 342. Fluid under pressure thence passes into the reservoir 306, while most of the liquid is permitted to flow 45 downwardly through the pipe 343 into the trap 305. Liquid deposited in the reservoir 306 by condensation or in any other manner is also free to flow into the trap 305 through the pipe 305a.

Upon the suction strokes of the piston 301, liquid is drawn from the reservoir 308 through the restricted passage in the tube 334, pipe 334a, the intake chamber 321 and past the open inlet valve 320 to the compression chamber 303 in the compressor, while the air or other fluid to be compressed is also drawn into said chamber by way 55 of the filter 324, passage 323, intake chamber 321 and past said inlet valve.

When the level of the liquid contained in the reservoir 308 has been lowered sufficiently by 60 withdrawal of liquid therefrom in the manner just described, the float 336 tilts the stem 336a about the pin 337 so as to lift the pin valve 340 from its seat. With the pin valve 340 unseated, the pressure of fluid in the reservoir 306, and in 65 the pipes 342 and 341 connected thereto, forces liquid from the trap 305 and pipe 305a upwardly through the cooling pipe 307 and past the valve 340 into the reservoir 308, thereby restoring the level of liquid therein so that the float 336 is 70 again raised to the position for seating the pin valve 340. It will be understood that the capacity of the trap 305 is such that, after liquid has been supplied from the trap to the reservoir 308 as just described, there will remain in said trap 75

a sufficient quantity of liquid to prevent escape of fluid under pressure from the reservoir 306 through the trap to the pipe 307.

The liquid in circulating through the pipe 307

5 is cooled with the aid of the fan 341 so as to ensure that the liquid supplied to the reservoir 308 will be at a low temperature and thus ready for further use in the compressor.

10 Means is thus provided for supplying compressing liquid to the compressor at the desired rate, separating the liquid discharged from said compressor, and for then cooling the liquid thus separated and rendering it available for further use in the compressor.

15 From the foregoing it will be apparent that my invention comprises an improved compressor operative to effect the substantially isothermal compression of air or other fluid by mechanical displacement of a body of liquid, which liquid is 20 also utilized as a cooling medium for dissipating the heat of compression, the compressor having means associated therewith for automatically controlling the compressor in accordance with the pressure of fluid supplied thereby, and for 25 unloading the compressor prior to cutting off the supply of power to the driving motor therefor, so that the compressor may always be unloaded before starting.

While several illustrative embodiments of the 30 invention have been described in detail, it is not my intention to limit its scope to these embodiments or otherwise than by the terms of the appended claims.

35 Having now described my invention, what I claim as new and desire to secure by Letters Patent, is:

1. In a gaseous fluid compressor, in combination, a fluid compressing piston for compressing fluid in a compression chamber, means operative 40 upon running the compressor for supplying liquid to the compression chamber at a restricted rate, said chamber having a liquid discharge communication, and means operated upon a predetermined increase in the pressure of fluid compressed by the compressor for opening said communication for permitting the discharge of the liquid supplied to said chamber.

2. In combination, a reservoir, a compressor adapted to supply fluid under pressure to said

reservoir, said compressor comprising a compression chamber communicating with said reservoir and adapted to contain a body of liquid, and a liquid displacing piston operable to reciprocate in said compression chamber for compressing fluid above said body of liquid, and means responsive to the pressure of fluid in said reservoir for varying the amount of liquid contained in the compression chamber and consequently the loading of the compressor.

3. In combination, a compressor having a compression chamber adapted to contain a certain quantity of liquid and a piston operative in said chamber for compressing gaseous fluid above said liquid, means for draining said chamber, a reservoir adapted to contain substantially the same quantity of liquid, means for supplying liquid thereto at a restricted rate, and means operative upon starting the compressor for establishing communication from said reservoir to said chamber, whereby said chamber is initially filled at a fast rate, and is further supplied with liquid at a restricted rate.

4. In combination, a gaseous fluid compressor comprising a compression chamber adapted to 25 contain a quantity of liquid and a liquid displacing piston operable to reciprocate in said compression chamber for compressing gaseous fluid above said liquid, means for supplying liquid to the compression chamber while the compressor 30 is running, and means responsive to a predetermined pressure of fluid compressed by the compressor for cutting off the supply of liquid to said compression chamber and for draining liquid therefrom for unloading the compressor.

35 5. In combination, a gaseous fluid compressor comprising a compression chamber adapted to contain a quantity of liquid and a liquid displacing piston operable to reciprocate in said compression chamber for compressing gaseous fluid 40 above said liquid, means for supplying liquid to the compression chamber while the compressor is running, and unloading means comprising a metering spring and valve means subject to the opposing pressures of said spring and of fluid 45 compressed by the compressor for controlling the draining of liquid from said compression chamber.

BURTON S. AIKMAN.
